UNITED STATES PATENT OFFICE.

OSCAR LASCHE, OF CHARLOTTENBURG, GERMANY, ASSIGNOR TO GENERAL ELECTRIC COMPANY, A CORPORATION OF NEW YORK.

CRANK-SHAFT.

1,251,389.

Specification of Letters Patent. Patented Dec. 25, 1917.

Application filed December 31, 1914. Serial No. 879,833.

To all whom it may concern:

Be it known that I, OSCAR LASCHE, a subject of the King of Saxony, residing at Charlottenburg, Germany, have invented 5 certain new and useful Improvements in Crank-Shafts, of which the following is a specification.

The present invention relates to multi-throw crank shafts more particularly for 10 use in connection with internal combustion engines having oppositely moving pistons, although it is not necessarily limited thereto.

In connection with such engines, especially multi-cylinder engines, it is desirable 15 for numerous reasons to have the crank shaft as short as possible, but heretofore it has been necessary to make them comparatively long in order to afford the necessary strength.

20 The object of the invention is to provide a crank shaft which is shorter in length than those heretofore made and which at the same time is materially stronger at the points where the greatest stresses occur.

25 For a consideration of what I believe to be novel and my invention, attention is directed to the accompanying description and the claims appended thereto.

Referring to the drawing, Figure 1 is a 30 side elevation of a multi-throw crank shaft embodying my invention; Fig. 2 is an end view thereof taken on line 2—2, Fig. 1; and Fig. 3 shows diagrammatically my improved shaft in connection with an internal combustion engine.

35 Referring first to Fig. 3, 4 indicates the cylinders of a two-cylinder internal combustion engine and 5 the oppositely moving pistons. 6 indicates a multi-throw crank 40 shaft having a central journal 7 and end journals 8 and 9, each supported in a suitable bearing 10. Between the central and each outside bearing the shaft is provided with three crank pins, a central crank pin 45 11 to which the lower pistons are connected by the connecting rods 12 and two outer crank pins 13 to which the upper pistons are connected by cross-heads 14 and side rods 15.

50 Referring now particularly to Fig. 1, it will be seen that the crank pins 13 are made very short as related to the crank pins 11

and that they are of greater diameter, their diameter being such that they intersect or overlap the journals. This overlapping of 55 the crank pins with the journals is a very important feature of my invention, as it adds great strength at a point where strength is needed, thereby materially increasing the margin of safety. At the same 60 time it permits the cheek plates 16 between the pins and the journals to be made much narrower than the remaining cheek plates 17 which also tends to shorten the over-all length of the shaft. The cheek plates 16 65 and 17 form the crank arms of the crank shaft. It is through them that the power is transmitted. If found desirable the journals may also be made larger in diameter so as to obtain a greater overlapping of the 70 same with the pins.

In Fig. 2 the extent of the overlapping of the journals and crank pins is very clearly shown, but it will be understood that the proportion of the parts may be varied to suit 75 different conditions met with.

In accordance with the provisions of the patent statutes, I have described the principle of operation of my invention, together with the apparatus which I now consider 80 to represent the best embodiment thereof; but I desire to have it understood that the apparatus shown is only illustrative, and that the invention can be carried out by other means.

85 What I claim as new and desire to secure by Letters Patent of the United States, is,—

A multi-throw crank shaft having crank pins displaced approximately 180°, and journals, said crank pins and journals being 90 connected to each other by cheek plates which form the crank arms of the shaft, the crank pins adjacent the journals being made relatively short as compared to the others and of such diameter as to overlap 95 with the journals, and the cheek plates between them being substantially narrower than the remaining cheek plates.

In witness whereof, I have hereunto set my hand this 23rd day of November, 1914. 100

OSCAR LASCHE.
